UNITED STATES PATENT OFFICE.

CLIVE W. LANPHERE, OF NEW YORK, N. Y.

PICKPROOF CYLINDER LOCK.

Application filed December 18, 1923. Serial No. 681,321.

This invention relates to cylinder locks and more particularly to a cylinder lock of the pin-tumbler type.

An object of my invention is to provide a cylinder lock which is simple in construction and incapable of being "picked".

Another object of my invention is to provide a cylinder lock having a key-plug which is capable of movement along its axis to actuate the lock mechanism.

Another object of my invention is to provide a cylinder lock of the pin-tumbler type with simple and effective means to prevent an actuation of the pin-tumblers without the use of a specially formed key.

Another object of my invention is to provide a cylinder lock having a key-plug capable of movement only upon the insertion of a key of the proper design.

A further object of my invention is to provide a cylinder lock having auxiliary tumblers mounted in the lock casing which normally engage the key-plug to prevent movement thereof, but which, when disposed in another position, permit free movement of the key-plug.

A still further object of my invention is to provide a cylinder lock having auxiliary tumblers which are adaptable for a lock having a key-plug which may be rotated or which may be moved longitudinally to effect the actuation of the lock mechanism.

Other objects of my invention will appear as the description proceeds.

It is well known that through the artifice of thieves cylinder locks of the pin-tumbler type may be opened by what is known as "picking" the lock. In locks of this type the picking operation is often performed by inserting a slender instrument into the key slot and moving the pin-tumblers to positions which release the key-plug. At the same time the key-plug is given a twist or rotary movement which acts to bind and hold the "picked" tumblers against return movement and since it is possible to produce a binding or what may be termed a lateral frictional engagement between the tumblers and the plug, the tumblers may be moved one after the other by means of the picking instrument until the key-plug is free to rotate with a consequent actuation of the lock mechanism.

Many efforts have been made to provide a cylinder-lock of the pin-tumbler type which

is incapable of being picked, but such devices of this nature of which I am aware are either very complex or else they do not accomplish the object for which they are intended.

In the lock which I have devised the casing is provided with auxiliary tumblers having either lateral or longitudinal movement. These auxiliary tumblers are additional to the usual pin-tumblers, which in many of the cylinder locks in use today have a perpendicular movement when the key cylinder is set with the key slot in a vertical position. Obviously if the cylinder is set at a different angle the tumblers would occupy different positions than the one mentioned and move accordingly. I have devised tumblers which move in different directions and therefore have to be actuated by a combination of forces applied in different directions. It will thus be apparent that in the lock which I have devised that it is practically impossible to "pick" it because the auxiliary tumblers which are loosely fitted do not extend as far into the key slot as the pin tumblers. If the auxiliary tumblers were first picked, turning the plug could not hold them as the closer fitted pin tumblers prevent sufficient movement of the plug. If the pin tumblers were first picked and moved to the position necessary to permit a slight movement of the key plug to hold the pin tumblers, any attempt to reach the short auxiliary tumblers with a straight pick would dislodge the pin tumblers and prevent moving the key plug. A right angle pick could not be used as the alternate projections on the opposite sides of the key slot would prevent it.

The invention will be more fully understood by reference to the accompanying drawings, in which—

Fig. 1 is a sectional view of a cylinder lock embodying my invention.

Fig. 2 is a view similar to Fig. 1 but having a key inserted to rearrange the tumblers to permit a rotation of the key-plug.

Fig. 3 is a transverse section taken on line III—III in Fig. 1.

Fig. 4 is a detail view of the key-plug which carries the pin-tumblers.

Fig. 5 is a top view of the device with the slide cover removed.

Fig. 6 is a perspective view of a rocking or auxiliary tumbler.

Fig. 7 is a perspective view of a spring which may be employed to actuate the rocking tumblers.

Fig. 8 is a sectional view of a lock having a key-plug which is capable of longitudinal movement within its casing and which also shows the rocking tumblers cooperating therewith to prevent such longitudinal movement.

10 Fig. 9 is a detail view of the longitudinally movable key-plug.

Fig. 10 is a transverse section taken on line X—X in Fig. 8, and

15 Fig. 11 is a perspective view of a rocking-tumbler which is employed in the longitudinally movable key-plug form of cylinder lock.

20 My invention may be applied to any well known form of pin-tumbler lock. The one shown for the purpose of illustrating the invention may comprise a cylindrical shell or casing 12 having a key plug 13 rotatably disposed therein. The casing is provided with sockets 14 to receive driver pins 15 and 25 their actuating springs 16. The key-plug is also provided with corresponding sockets or apertures 17 communicating with a key slot 18 for the reception of pin tumblers 19. The driver pins and their actuating springs 30 may be retained in the casing by any well known means and in the lock which I have devised there may be employed for this purpose a slide cover 20 which may snugly fit a slot 20' in the casing 12.

35 One or more annular grooves 21 may be formed in the plug and so positioned that when the plug is properly inserted into the casing a groove 21 will be disposed, when desirable, between two pin tumblers. At 40 one side of each groove a notch 22 is formed and a guard or what may be termed a rocking or auxiliary tumbler 23 is pivoted in the casing and normally positioned with its end 24 disposed in a notch 22. Each rocking tumbler 45 may be disposed in a transverse slot 25 in the casing and may be pivotally supported or hinged by means of a pin 26, which for illustrative purposes is shown integral with the rocking tumbler, on shelves 26' at 50 the upper ends of the slots 25. A spring 27 may be provided to normally retain the end 24 of the tumbler 23 in the notch 22, the spring being disposed in a transverse slot 27' in the casing. The spring may be supported by means of shoulders 28' integral therewith, which are adapted to rest on shelves 28" at the lower ends of the slots 27'. The 55 rocking tumblers are so disposed in their slots as to have a rocking movement which is either in the direction of the longitudinal axis of the casing or laterally, while the movement of the pin-tumblers may be such that they move in a direction which is transverse to such axis. It is thus evident that 60 the pin-tumblers and the rocking tumblers

have movements which are in different directions.

It will be noted that as shown in the drawing a rocking tumbler may be provided adjacent to each of a plurality of the pin tumblers 19, the ends of the rocking tumblers projecting different distances into the plug, the notches being proportioned accordingly and so positioned in the plug as to lie across the key slot 18. Thus a key 18' having the proper configuration may be provided so that when it is inserted into the key slot the portions or wards 28 on the key will engage with and move the rocking tumblers in opposition to the springs 27. The key may be properly shaped to also move the pin-tumblers in the usual manner and, consequently, the driver pins 15 to such positions as to allow a rotary or other movement of the plug 13. The rocking tumblers by reason of their contact with the key will then have been moved out of the notches 22 and will permit a movement of the plug because of the annular grooves 21. The key may be provided with suitably disposed notches 29 so that when turned with the plug no interference will occur between the key and the rocking tumblers, or the key may be so disposed in the plug that the bottom thereof will, when the key or plug is rotated, not interfere with the rocking tumblers.

My invention, as shown in Figs. 8 to 11, may include a pusher key plug 13, a longitudinal movement of which may be employed for various purposes. As illustrated, the constructional details in the main are similar to the form of lock previously described, however, in adapting the rocking tumblers to the pusher key-plug type of cylinder lock, I find it desirable to modify the arrangement of these members as well as their operation and coaction with the plug so as to secure the desired result. To this end the rocking tumblers 23 are pivotally mounted in slots 25 in the casing 12 in such a manner that they may be swung about hinges or pivots 26 transversely of the casing instead of along the axis of the casing as in the lock previously described. In order to provide for such a movement of the rocking tumblers their lower ends 24 may be normally disposed in notches or slots 31 extending across the key-plug. The rocking tumblers may be restrained in the notches by springs 27 which may be suitably disposed in transverse slots 27' in the casing, the springs being supported by shoulders 28' integral therewith. The rocking tumblers in this device may be provided with shoulders or pins 26 which may engage shelves 26' in the upper ends of the slots in which the tumblers are disposed.

Communicating with the notches 31 are slots 32 at right angles thereto, into which the ends 24 of the rocking tumblers move upon the movement longitudinally of the

key-plug within the casing. In order to move the rocking tumblers transversely by engagement with the key, the forward edge thereof for a portion of its length, or that edge facing the side of the key, may be provided with a rounded or double-bevel edge 38.

The operation of the lock just described is as follows: Upon the insertion of a key 10 into the key-way, the end of the key engages the sides of the rocking tumblers and pushes them into registry with the longitudinal notches or slots 32. The continued forward movement of the key into the key-way raises the pin-tumblers into proper position so that when the head of the key engages the end of the key-plug a forward thrust upon the key will cause the key-plug 15 to move longitudinally within the casing, whereby the lock mechanism may be actuated. The depth of the longitudinal slots 32 may be such as to provide for the desired longitudinal movement of the key-plug. Although the longitudinally movable key-plug is illustrated as circular in cross-section, it is obvious that by reason of the movement which is imparted thereto it may be of other desirable shapes, such as rectangular, oval, etc. 20 The return of the key-plug to its initial position may be effected by means of a spring 34 which may be disposed in a transverse slot 35, suitably disposed in the casing. The lower end of the spring may extend into 25 a transverse slot 36 in the key-plug so that when the latter is moved longitudinally within the casing the spring 34 will be placed under tension and when the pressure upon the key is removed the energy thus 30 stored in the spring will return the plug to its initial position.

If desired the cylinder lock may be provided with the longitudinally movable key-plug without employing the auxiliary tumblers. Furthermore a cylinder-lock may be 40 provided which employs the auxiliary tumblers alone.

Many modifications of the invention described above will suggest themselves to those skilled in the art, but such as come 45 within the terms of the appended claims are considered as falling within the spirit and scope of my invention.

What I claim is:—

50 1. A pin-tumbler lock comprising a casing, a key plug therein, driver pins in said casing, said pins being normally positioned to prevent movement of said key plug, and supplemental means carried by said casing and movable at a different angle from said driver pins, said pins being disposed adjacent said means and arranged to prevent access to the same by a pick or other improper instrument.

60 2. A pin-tumbler lock comprising a cas-

ing, a key plug, locking members for normally preventing movement of said key plug, and a lock bar carried by said casing and terminally retained to prevent movement of said key plug.

70

3. A pin-tumbler lock comprising a casing, a key plug, driver pins normally positioned to prevent movement of said key plug, said driver pins being movable by engagement with a special tool, and supplemental members carried by said casing, said driver pins being disposed in advance of said members, whereby picking of the lock is practically impossible.

75

4. A pin-tumbler lock comprising a casing, a key plug therein, driver pins normally positioned to prevent movement of said key plug, said driver pins being movable by engagement with a special tool, and supplemental members carried by said casing and comprising spring-actuated arms, whereby movement of said key plug except by said tool is rendered practically impossible.

80

5. A pin-tumbler lock comprising a casing, a key plug therein, driver pins normally positioned to prevent movement of said key plug, said driver pins being movable by engagement with a special tool, notches in said key plug, and guard members carried by said casing for engaging said 95 notches to prevent movement of said key plug except by said tool.

90

6. A pin-tumbler lock comprising a casing, a key plug therein, driver pins normally positioned to prevent movement of said key 100 plug, said driver pins being movable by engagement with a special tool, and guard members pivotally supported by said casing and engaging said key plug to prevent movement thereof except by means of said tool.

105

7. A pin-tumbler lock comprising a casing, a key plug therein, said casing having a plurality of driver pins to normally prevent movement of said key plug relative to said casing, an instrument for actuating said 110 driver pins to permit relative movement of said casing and said key plug, and guard members pivotally carried by said casing and engaging said key plug, said members being operable by said instrument.

115

8. A pin-tumbler lock comprising a casing, a key plug therein, said casing having a plurality of driver pins to normally prevent movement of said key plug relative to said casing, an instrument for actuating said 120 driver pins to permit relative movement of said casing and said key plug, notches in said key plug, guard members carried by said casing and having portions thereof normally disposed in said notches and in the 125 path of operative movement of said instrument, and means upon said instrument for disengaging said guard members from said notches.

125

9. A cylinder lock comprising a casing and 130

a key plug therein, said casing and plug having interlocking means for preventing movement of said plug within said casing, a portion of said means being capable of transverse movement from interlocking engagement with said key plug in one direction and the other portion thereof carried by said casing and being capable of transverse movement in another direction from interlocking engagement with said key plug.

10. A cylinder lock comprising a casing, a key plug movably mounted in said casing, driver means disposed vertically within said casing and normally engaging said key plug to prevent movement thereof, and auxiliary means vertically disposed and supported by said casing, said auxiliary means being positioned behind said driver means and movable at an angle with respect thereto, where-
20 by picking of said lock is practically im-
possible.

11. A cylinder lock having a key plug, means carried by the casing of said lock for locking said plug from movement, said means having portions thereof movable transversely with respect to said plug and portions movable in the arc of a circle.

12. A cylinder lock comprising a casing and a key plug movably mounted in said casing, and means for preventing longitudinal movement of said plug within said casing, said means being mounted in said casing and capable of movement transversely of said plug.

13. A cylinder lock comprising a casing and a key plug movably mounted in said casing, means carried by said casing and projecting therefrom into said plug for preventing movement thereof, a portion of said means movable in a path at substantially right angles with respect to the longitudinal axis of said plug and disengaging the plug

completely to permit movement thereof and the remaining portion of said means movable in the arc of a circle and remaining in engagement with said plug but permitting movement thereof.

14. A cylinder lock of the pin-tumbler type having a latch disposed parallel to and between the driver pins therein and capable of movement in the arc of a circle.

15. A cylinder lock of the pin-tumbler type and having driver pins, and also having pivotally mounted tumblers disposed between said driver pins.

16. A cylinder lock of the pin-tumbler type having driver pins, a pivotally mounted tumbler disposed between said driver pins and capable of a movement at a different angle than the pins.

17. A lock of the pin-tumbler type having rocking tumblers engaging the key plug in one position to prevent movement thereof and when disposed in another position permitting movement thereof.

18. A lock of the pin-tumbler type comprising a casing, a key plug therein, and tumblers pivotally supported by said casing and engaging said key plug.

19. A lock comprising a casing, a key plug in said casing, driver pins carried by said casing and normally engaging said key plug to prevent movement thereof, pin tumblers carried by said plug and cooperating with said driver pins, said key plug being longitudinally movable within said casing when said driver pins are disposed in unlocked position by a key of the proper configuration engaging said pin tumblers.

In testimony whereof, I have hereunto subscribed my name this 13 day of December, 1923.

CLIVE W. LANPHERE.
